NEEDLE, THREAD, AND THIMBLE KIT

George J. Dillemuth, Tiller, Oreg.

Application November 21, 1950, Serial No. 196,900

3 Claims. (Cl. 223—106)

1

This invention relates to a needle, thread and thimble kit.

It is an object of the present invention to provide a needle, thread and thimble kit wherein the needles and thimble are retained on an attachment adapted to be combined with the spool of thread and wherein the portion thereof containing the needles enters the center hole of the spool.

It is another object of the present invention to provide in an attachment adapted to support needles and a thimble which can be fixed to a spool wherein there is separable top parts normally held together by spring action to confine the thimble and wherein upon release of one of the parts against the spring action the thimble can be released and access can be had to the chamber portion confining the needles.

Other objects of the present invention are to provide a combined needle, thread and thimble kit which is of simple construction, utilizes the spool as the supporting body, inexpensive to manufacture, has a minimum number of parts, easy to operate, compact, durable, of pleasing appearance and efficient in operation.

For other objects and for a better understanding of the invention, reference may be had to the following detailed description taken in connection with the accompanying drawing, in which

Fig. 1 is a perspective view of the attachment for the spool with the thimble disposed thereon.

Fig. 2 is an enlarged top plan view of the attachment illustrating the manner in which one of the parts is separated from the other part to provide access to the needle compartment.

Fig. 3 is a vertical sectional view of the attachment supported on the spool and as viewed on line 3—3 of Fig. 2.

Fig. 4 is a fragmentary sectional view taken on line 4—4 of Fig. 2 and through the hinge connection of one of the parts with the other part.

Referring now to the figures, 10 represents an attachment for supporting a thimble 11 and needles 12. This attachment comprises a top plate part or portion 13 and a hollow depending needle retaining portion 14 flanged at its upper end, as indicated at 15, and connected to the underside of the top plate 13. The hollow depending portion 14 serves to confine the needles 12 and the bottom thereof is closed, as indicated at 16. On the bottom is a resilient support 17 for receiving the points of the needles 12 and to prevent the same from becoming blunted.

The hollow depending portion 14 fits within a

hole 18 of the spool 19, as shown in Fig. 3. The top plate 13 has struck down projections 21 which pierce the upper end of the spool 19 to retain the attachment 10 in place upon the spool and against rotational and axial displacement therefrom.

The top plate 13 has a central hole 22 through which the needles 12 may pass. This top part also has a semi-circular flange 24 projecting upwardly from one side thereof and to which the end of an arcuate-shaped spring 25 is attached. A movable element or cover of a little more than half circular shape, and as indicated at 25' is hingedly connected to the top plate 13 by a pivot grommet 26. This cover has an upstanding peripheral flange 27 about part of which the spring 25 extends and is locked therewith, as indicated at 28. The action of the spring 25 is to urge the cover 25' into a closing position over the opening 22. The flange 27 of the cover 25' has a handle projection 27' by which the cover can be moved to its open position, as indicated in dotted lines in Fig. 2, and against the action of the spring 25.

Struck upwardly from the top plate 13 is an arcuate portion 31 under which one side of thimble 11 can be placed. On the cover 25' is an arcuate portion 32 adapted to extend over the opposite side of the thimble 11 whereby to hold the thimble 11 in place upon the attachment. The function of the cover 25' is thus to hold the thimble 11 in place and at the same time to serve as a cover for the needle compartment. Thread 33 is coiled upon the spool 19.

It will be apparent that the attachment 10 can be sold as a separate unit and when inserted in the spool 19 a combined needle, thread and thimble kit is provided.

The spring 25 is made secure upon the flange 24 by a struck projection 34 and by the passage of the end of the spring through openings in the flange, as indicated at 35.

While various changes may be made in the detail construction, it shall be understood that such changes shall be within the spirit and scope of the present invention as defined by the appended claims.

What is claimed is:

1. In combination, a spool having a central opening therein and an end face, an attachment comprising a top plate and means securing said top plate to the end face of the spool, said top plate having an upstanding projection adapted to receive one side of a thimble, a movable element hingedly connected to the top plate and

having a projection adapted to engage the other side of a thimble and spring biasing means urging together the movable element with its upstanding projection toward the upstanding projection of the top plate whereby to secure the thimble to the attachment.

2. In combination, a spool having a central opening therein and an end face, an attachment comprising a top plate and means securing said top plate to the end face of the spool, said top plate having an upstanding projection adapted to receive one side of a thimble, a cover member hingedly connected to the top plate and having a projection adapted to engage the other side of a thimble and spring biasing means urging together the cover member with its upstanding projection toward the upstanding projection of the top plate whereby to secure the thimble to the attachment, said top plate having a central opening, a depending hollow portion connected to the underside of the top plate under the opening and providing a compartment for needles, said portion adapted to extend through the central opening of the spool and said cover member adjustable over the opening to retain the needles within the compartment.

3. In combination, a spool having a central

opening, a depending hollow needle retaining portion extending into the central opening, a top plate secured to the open upper end of the depending hollow portion, means connecting said top plate to the end of the spool, said top plate having a central opening aligned with the opening of the hollow needle retaining portion, a cover member pivotally connected to the top plate portion and movable laterally over the central opening of the top plate portion between closing and open positions, spring means extending between the cover member and the top plate portion urging the cover into its closing position, said top plate portion and said cover member having upstanding projections adapted to receive and retain a thimble when the cover member is in its closing position.

GEORGE J. DILLEMUTH.
